Patented Apr. 10, 1923.

1,451,670

UNITED STATES PATENT OFFICE.

ROBERT MACPHERSON, OF WORTHING, AND WILLIAM E. HEYS, OF BUSHEY,
ENGLAND.

ANTISEPTIC AND INSECTICIDAL SOAP OR COMPOSITION.

No Drawing.

Application filed January 16, 1923. Serial No. 613,060.

To all whom it may concern:

Be it known that we, ROBERT MACPHERSON, a resident of Worthing, in the county of Sussex, England, and WILLIAM EDWIN HEYS, a resident of Bushey, in the county of Hertford, England, both subjects of the King of Great Britain and Ireland, have invented a new and useful Improvement in Antiseptic and Insecticidal Soap or Composition, of which the following is a specification.

This invention relates to antiseptic and insecticidal soaps or compositions, and has for its object to provide an improved soap or composition having high antiseptic and insecticidal properties.

According to the invention, the antiseptic and insecticidal soap or composition comprises soap, alkali benzoate and tar. The soap or composition may be prepared by a mechanical admixture of soap, a suitable benzoate and tar, or by saponifying an admixture of fatty acids, benzoic acid and tar.

By way of example, the improved soap or composition may comprise hard (soda) or soft (potash) soap 80 parts, sodium or potassium benzoate 10 parts, and birch tar 10 parts, which may be thoroughly incorporated by any appropriate known means. Alternatively, we may prepare the composition by treating a properly proportioned mixture of fatty acids, benzoic acid and birch tar with an alkali, such as a soda lye or potash lye in sufficient quantity to saponify the fatty acids and convert the benzoic acid into an alkali benzoate. In such method saponification of the admixture must be effected by the "cold process" or in any known way which does not involve boiling or the salting out of the soap or composition.

Although we prefer to employ birch tar in the manufacture of the improved soap or composition, we may, if desired, employ any other vegetable tar, or we may employ gas or any other mineral tar.

It will be understood that in the term fatty acids, used in the above description and in the following claims, we include the surrogates of fatty acids.

What we claim as our invention and desire to secure by Letters Patent is:—

1. A saponaceous antiseptic and insecticidal composition comprising soap, a fixed alkali benzoate, and tar in the proportions of eighty parts of soap, ten parts of fixed alkali benzoate, and ten parts of tar.

2. That process of producing a composition of soap, fixed alkali benzoate and tar which consists in treating a mixture of proper proportions of fatty acids, benzoic acid and tar with a fixed alkali in sufficient quantity to saponify the fatty acids and convert the benzoic acid to a fixed alkali benzoate, the quantities of the mixture ingredients and the fixed alkali being proportioned to produce a resultant composition containing substantially eighty parts of soap, ten parts of fixed alkali benzoate and ten parts of tar.

3. A saponaceous antiseptic insecticidal composition comprising soap, a fixed alkali benzoate, and tar, the quantities of the tar and fixed alkali benzoate being substantially equal, and the combined quantities of the fixed alkali benzoate and tar being substantially one-fourth of the quantity of soap.

In witnesses whereof we have hereunto set our hands.

ROBERT MACPHERSON.
WILLIAM E. HEYS.
